UNITED STATES PATENT OFFICE

WILLIAM H. SOMMER, OF PEORIA, ILLINOIS

FENCE STRUCTURE

Application filed May 2, 1930. Serial No. 449,311.

This invention has reference to a fence structure.

A structure such as I have in mind, is that type of a fence including longitudinal strand or line wires and transversely disposed stay or picket wires, the latter being straight single pieces of wire which have their ends preferably wrapped or coiled about the marginal strand or line wires, and at their points of intersection or crossing of the strand or line wires are connected to such strand wires by wire staples.

The principal object of the invention is to so connect the stay wires, with the strand wires, at their points of intersection or crossing, as will provide a proper and effective lateral support for said stays at such points of intersection with the strands, and thereby effectively prevent any possibility of the stays leaning in either lateral direction from the perpendicular.

I accomplish the foregoing objects by employing wire staples, which, when viewed, let us say from the strand wire side of the fence, have substantially the shape or outline of the letter Z, comprising upper and lower clinching portions and an angular portion connecting said clinching portions and wherein the clinching portions of the staples, adjacent to and connecting the angle portions thereof, lie closely or in abutting relation against the stay wire and whereas, the ends of the clinching portions do not. Thus by alternating the successive staples (in this manner—Z. Z.) throughout the stays, whereby the angle portions of the successive staples are disposed in opposite directions, I provide, through the medium of the clinching portions of the staples, proper lateral supports for the bodies of the stays at each strand wire, which will prevent the stays leaning in either lateral direction from the perpendicular.

I am aware that fence structures which embody strand and stay wires are not new; also that the use of staples of the design I have shown, is not new. And yet, I am also aware that fence structures of the type disclosed, where the staples are applied uniformly and alike throughout the stays, at

their points of intersection or crossing of the strand wires, that the stays do not have proper lateral support and that as a result, the stays lean in both lateral directions from the perpendicular and the fence thereby, is not only unsightly but cannot be properly stretched by the average person.

That the invention may be more fully understood, reference is had to the accompanying drawings, forming part of this description, illustrating a preferred embodiment of the invention, in which:

Fig. 1 is a view of a section of "stiff-stay" fence constructed in accordance with my invention;

Fig. 2 is a detail view of a portion of a stay wire and several strand wires, connected in accordance with my invention, and as the same appears embraced by the line 2—2, Fig. 1;

Fig. 3 is a detail of the staple connection, see the arrows 3—3, Fig. 2;

Fig. 4 is a detail of the staple connection, see the arrows 4—4, Fig. 2, and

Fig. 5 is a detail, in section, to show the lateral support provided by the clinching portions of the staple, for the stay wires.

Like characters of reference denote corresponding parts throughout the figures.

In the drawings, the strand wires, including the marginal and intermediate line wires are designated 1. The stay wires are designated 2 and the staple tie wires are designated 3. The latter comprise the clinching portions 4 and the angular portion 5. In applying the staples, the clinching portions 4 are preferably applied to the stays and the angular portions 5 are applied preferably against the strands and unite with the clinching portions 4 at the stays. It is to be noted, that the clinching portions 4 of the stays connected to and adjacent to the angle portions 5, see Fig. 5, lie closely or in abutting relation against the stay wire, as at 6, and that the end portions 7 of the clinching ends 4, do not. Thus, by alternating the staples, with each succeeding strand wire, see Fig. 2, I alternate the supporting portions of the staples, whereby to give a proper lateral support for the stays and prevent any possibility of the stays lean-

ing in either lateral direction from the perpendicular.

The stay wire, is of one piece throughout from one marginal wire to the other, as distinguished from a stay made up of a series of sections the meeting ends of which are usually wrapped with each other about a strand wire. Furthermore, it is to be understood that the stays are single straight pieces of wire, but which, at the intersection of the strands, where, due to the application of the staples slight kinks may appear due to the action of dies used to apply the staples.

Furthermore it is to be understood that, in the manufacture of fencing various spacings between the strands or lines are employed—i. e., a close spacing of a series of the strands at the bottom of the fence, which may be uniform or vary for a given number of strand or line wires and then the spacing of a second series at graduated distances apart to the top of the fence. Where the strands or line wires are spaced at one inch apart at the bottom of the fence there is little, if any need, to reverse the successive staples of such series of strands, due to the rigidity of the fence, and due to such close spacing, but as the spaces between a second series of the strand or line wires become greater, to prevent leaning of the stays in either lateral direction from the perpendicular, reversal of the staples is desired and in fact necessary. Therefore, more than one reversal of the staples throughout the stays is necessary, if leaning of the stays is to be prevented and the arrangement of the staples can, therefore, be modified to meet the conditions in different spacings between the strand or line wires, without departing from the spirit and scope of the invention.

Furthermore, by reference to Figs. 2 and 5, and particularly the latter figure, it is to be observed that the clinching portions 4 of the staples are spaced from the strand or line wires 1, which has for its object to allow for the necessary flexibility in the fence when erecting the same over hilly or uneven ground.

What I claim is:—

In a fence, including a series of spaced strands and stays, staple-ties for connecting the stays to the strands at the points of intersection thereof, including inclined portions which extend across the stays and clinching portions disposed on opposite sides of the strands and clinched to the stays, the inner faces of the free ends of the clinching portions of the staples being slightly spaced from the stays, and the inclined portions of the staples alternately extending in opposite directions on the various stays thus preventing leaning or canting of said stays.

WILLIAM H. SOMMER.
